WASHING MACHINE FOR WINDOW BLINDS

Ogle F. French, Wichita, Kans.

Application June 21, 1945, Serial No. 600,805

8 Claims. (Cl. 134—108)

1

This invention herein disclosed relates to a washing machine for window blinds, similar to that of the Venetian type, and has for its principal object, to speed up the work to avoid water spots, and furthermore to economize the cost of such work.

A further object of this invention is to provide a series of chambers coacting and being aligned for step-by-step continuous operation, namely, first to wash and sterilize the blinds, second, to rinse thoroughly, third to evaporate rapidly to a dry state to avoid water spots and from thence outward for delivery.

A still further object of this invention is to provide efficient means to heat water for washing purpose and also provide for a current of heated air and circulate the same through the drying chamber for rapid evaporation of moisture from the blinds after washing and rinsing the same to avoid marring or otherwise spoiling the finished surface of the blind louvers as originally treated.

A still further object of this invention is to construct a unitary laundry machine for cleaning window blinds made from slats, the process required is a means to economize the cost of labor to operate the machine, and furthermore the cost of manufacturing the units of the machine is comparatively inexpensive and requires but a narrow strip of floor space for its installation compared to that required for other complete laundry equipment for work in general, and such general laundrying is not included in this invention.

These and other objects will hereinafter be more fully explained, reference being had to the accompanying drawings forming a part of this specification, and in which like characters will apply to like parts in the different views.

Referring to the drawings:

Fig. 1 is a side elevation of the invention embodying the components of the machine with respect to washing, rinsing, and drying blinds continuously as fed therein.

Fig. 2 is a top plan view of Fig. 1, showing the motor and pipe circulating system, parts removed for convenience of illustration.

Fig. 3 is a plan view of the washing chamber, water tank and heating pipes.

Fig. 4 is an end view of Fig. 3, parts removed for convenience of illustration.

Fig. 5 is a plan view of the rinsing chamber and water tank therebeneath.

Fig. 6 is a fragmentary side view of Fig. 5

2

showing end doors flaps in their open position, as forced by the blinds.

Fig. 7 is a vertical section at the upper extremity of the washing or rinsing walls, said view including one of the spray nozzles.

5 Fig. 8 is a fragmentary inside elevation of Fig. 7.

Fig. 9 is an enlarged section of the trolley and track taken on line 9—9 in Fig. 14.

10 Fig. 10 is a section longitudinally of the track crossing the rockable joint on line 10—10 in Fig. 14.

15 Fig. 11 is a sectional view taken on line 11—11 in Fig. 14 to illustrate the trolley carrying means for the free end of the track switch, parts removed for convenience of illustration.

Fig. 12 is an enlarged end view of the drying chamber, including a portion of the hot air duct.

20 Fig. 12—A is a modification for the drying chamber eliminating the heated air circulating ducts by substituting infra red lamps therefor.

Fig. 13 is a plan view of the trolley chain race, motor and gear ratio to actuate the travel of the chain.

25 Fig. 14 is an enlarged side view of the track switch mechanism, parts removed for convenience of illustration.

Fig. 15 is a plan view of Fig. 14.

Fig. 16 is a sectional view as modified to eliminate the track by the adoption of a hook to carry 30 the blinds direct by the chain.

Fig. 17 is a transverse view to that shown in Fig. 16, showing the hook as detachably engaged on the chain.

35 As a more concise description of the drawings, it will be seen that the invention consists of, washing, rinsing, and drying chambers, all being straight aligned to work coordinately as a unit for a final result with respect to washing blinds for windows or the like.

40 Attention is first directed to the structure of the said blinds as comprising a plurality of slat like elements A made of wood or other materials, and being secured together in parallelism and in spaced relation by flexible strips B transversely

45 crossing the strips oppositely with respect to their edges and being secured thereto to permit simultaneous rocking of the slats to an open or closed position so that spray washing of the blinds will be therethrough from edge to edge for the sides of the slats and including the flexible strips.

50 To accomplish cleansing of the blinds by spray washing, it will be seen that the components of the said washing machine consists of a U-shaped washing chamber, later described, and being vertically mounted on a water tank 1, said tank hav-

ing a tubular heating pipe 2 consisting of straight portions C of suitable length and diameter that are connected end to end correspondingly by return arced joints D for continuous circulation of a current of heat through said pipe and outward therefrom through a vertically disposed pipe 3 that is connected to the discharge end of first said pipe assembly and from thence to a chimney or the like, while the other or intake end of said pipe 2 has a gas burner 4 inserted therein and a gas supply pipe 5 as fuel feed for the burner, said pipe having a valve control 6 for the gas, whereby water contained in the tank may be heated to a high degree of temperature, and then charged with an efficient washing compound and continuously circulated by a force pump to quickly cleanse the blinds as sprayed by the water while said blinds are passing through the washing chamber, the conveyance for the blinds later described.

Said washing chamber as heretofore stated is vertically positioned and seated on bars 6' centrally crossing the upper extremity of said tank and the said chamber consisting of two hollow metallic members as legs 7 that are spaced apart and secured by a hollow bottom portion as a crotch 7', the space being sufficient for one set of blinds to pass therebetween and also for a plurality of spray nozzles 8 communicating with their respective hollows of said members and extending inwardly toward each other from the confronting sides of said hollow members, said hollow members being so positioned and connected will function as sides and bottom of the washing chamber, the sides of which are secured by brace members 8'. The ends of the chambers are closed by rubber flaps 9, having one edge of each secured to its respective end of the side walls by a strip 9', said flaps, adapted to flex inward and outward as the blinds pass therebetween on their path through the said washing chamber. The purpose of the flaps is to restrict the water spray from freely passing outward from the ends of the chamber and to retain the acquired heat from the temperature of the water within said chamber but free to pass outward through the opening at the upper extremity of the washing chamber but being in contact with the blinds on its path upward. The water pressure for the spray nozzles is produced by a pump 10 that is actuated by a motor 11, said pump being connected to a pipe line comprised of a joint 12 that connects the pump to one side of the washing chamber to build up pressure in the hollow thereof while the water supply is taken from tank 1 by pipe joints 13 for continuous circulation of the hot water that is treated with washing compound as heretofore stated to cleanse the blind section conveyed through the washing chamber in a continuous aligned movement. To discharge the water from the tank, it will be seen that by opening valve 14 the tank will drain through pipe portion 15, it being understood that the water from the washing chamber is free to return to the tank as it drains from the bottom of said chamber as a result of the spray action.

Said blinds as washed will enter a rinsing chamber that is vertically mounted on a tank that functions as a catch basin 16 for the rinse water as sprayed on the blinds, and from thence outward, through a waste pipe 17, otherwise it will be seen that the rinsing chamber structurally is the same as the washing chamber, but supplied with city water pressure line 15', while its tank is also reduced in size and merely to function as a

catch basin with continuous drainage through its respective said waste pipe 17.

After a thorough rinsing of the blinds, the same are transferred into a drying chamber by a relay switch later described, said chamber comprising side walls 18 spaced apart, the upper extremity of which is enclosed by a top member 19 through which extends vent openings 20, said openings being provided with lids 21 to open as an exhaust for moisture evaporated by a current of heated air in the process of drying the blinds and the said side walls being closed at their lower extremity by a metallic bottom 22 seated on a support 23. Spaced upward from said metallic bottom is a perforated plate 24, said plate being secured to the side walls of the drying chamber and braced by metallic bars 25 extending across the drying chamber from wall to wall whereby a fire-proof chamber 26 is arranged. Positioned outward and along one side of the drying chamber is a mechanical heat circulating device consisting of a motor 27 as actuating means for a fan 28, the exhaust neck 29 of which communicates with a heating device 30 and from thence into a duct 31, the duct exhausting air of a high degree of temperature into and through said chamber 26 and upwardly through the perforations 24' of plate 24 into the drying chamber 26' above described, and when the blinds are dried they are removed from track terminals E that extend outward from the drying chamber to where they rest on a beam 32 which is carried by posts 33. It will be seen in Fig. 1, that blinds are conveyed through the washing unit as a whole on a track 34 positioned above the washing and rinsing chambers while the drying chamber extends to a higher plane to provide room for a rockable switch mechanism later described. Said track and race 35 spaced vertically are supported at their forward ends a spaced distance from the washing chamber by a vertically disposed post 36, while the other ends of said track and race are carried by the drying chamber as follows: It will be seen that the race a spaced distance 40 inward from its other end as at I slants upward and toward the drying chamber where its terminal end seats on the upper extremity of the drying chamber, said race being so formed is means to provide room for the track switch mechanism and also to position the track and race in parallelism from the forward ends to where the slant begins. The said race is formed from a pair of L-shaped members spaced apart to provide an opening F between their confronting horizontally disposed legs 38 while the other legs 45 upwardly extend to form a channel in which to position an endless chain belt 39 that engages on rollers 40 and sprockets 41 journalled in bearings 42 upwardly extending from the vertically disposed legs 38, said rollers to carry the weight of the upper portion of the belt while the lower portion thereof slides on the legs horizontally disposed.

As traveling means for the chain belt is through the medium of a motor 44 positioned on the chain race adjacent the first named end thereof to actuate a train of gears 45, 46, 47, and 48 to reduce the speed travel of the chain belt as the blinds are to move slowly through the 50 washing, rinsing and drying chambers.

To convey the blinds it will be seen that trolleys are provided to carry the blinds, said trolleys comprising a sheave 49 to roll on the track, said sheave being journalled in a bearing 50 having a hook 51 downwardly extending to engage with

a hook G of a clip 52 that has a loop H in which a carrying bar 53 for the blind will engage, while on the other or upper end of the bearing is a finger J of sufficient length to enter a link of the chain as moving means for the clip or clips to convey the blinds pendants through the washing and rinsing chambers. Immediately after the rinsing, the finger of the clip automatically releases from the chain belt due to a downward incline K along the upper edge of the track as shown in Fig. 14 and co-incident therewith the blinds thus detached are forced onward by edgewise contact and being directed by a rockable portion of the track that functions as a switch 54 to fill a series of tracks 55 positioned in the drying chamber in spaced relation across said chambers and being in parallelism and extending outward from the terminal end of said drying chamber as shown in Figs. 1 and 2, at which outward point the blinds when laundered are assembled for delivery. A portion of the other ends of said tracks are positioned convergently and terminating as indicated by a dotted arcuate line 55' so that the rocking movement of the free end of the switch member will circumscribe and register rigidly but releasable in consecutive order with the ends of the said series of tracks that terminate along said dotted line 55' as above described, whereby the said tracks of the drying chamber are co-ordinately filled with washed blinds to dry the same continuously step by step repeatedly during the washing action of the machine.

As a carrying means for all tracks, it will be seen that hanger bars 56 have their upper ends rigidly secured to their respective chain race as in Fig. 9 and ceiling or top enclosure of the drying chamber as in Fig. 12 while their lower ends have an offset L to space the bar portion from the track, as well as to provide room for sheaves to roll in the clear while conveying the blinds along said tracks 34 and 55.

In Figs. 9, 10, 11, 14, and 15 is shown the components of a transfer switch mechanism consisting of a track portion as a switch 54 rockably joined to a single track 34 between said rinsing and drying chambers, the knuckle joint M of which is concavo-convex abutting for rocking movement oppositely on a horizontal plane, said switch member being rockably carried at one end by a U-shaped frame 56, the legs of which extend horizontally and vertically aligned in spaced relation, the upper leg having an extension N positioned at right angle on the same plane and has a stud 57 pivotedly seated in a socket 58 that is secured to the chain belt race while the lower leg is secured rigid to the switch a spaced distance inward from its rockable connection with the single track, said space being equal to the length of the offset of the upper leg, above referred to, to rock or swing the switch oppositely on a horizontal plane by rocking the frame manually, it being understood that the legs of the U-shaped frame 56' will straddle the slanting portion I of the said race to facilitate an equal distance swing of the switch oppositely as required for registry engagement of its free end with the adjacent terminal ends of the series of tracks in the drying chamber so that the trolleys will travel smoothly from the switch element onto said track series selectively or consecutively from track to track of the series. It will be seen that the other end of the transfer switch is carried by a trolley later described that connects the outer or free end of the transfer switch

to an arcuate track 59 that is dimpled at spaced intervals along its underside as at P, and the said track at its terminal ends being secured to terminal ends correspondingly of a bar 60 that crosses the elevated portion of the chain belt race and being secured thereto at the longitudinal center of said bar. As above stated with respect to the trolley, it will be seen that it consists of a bar 62 having an offset R to connect the same to the free end of the switch as shown in Fig. 11 to avoid obstructing the trolley roller 63, said roller being journaled between a pair of bearings 64, while the lower ends of said bearings are secured to the upper end of said offset bar whereby the switch is easily rocked to registry with adjacent ends of the drying chamber series of tracks, and the said trolley has a spring tensioned stay bolt 65 to seat in the dimples at the instant of end registry of the switch and tracks, consecutively or selectively as the case may require.

To move the switch from its locked position there is provided a rod or chain 66 with which to draw the bolt from engagement with the dimples to free the trolley for further movement of the switch manually.

As a modification for the drying chamber, attention is directed to Fig. 12—A in which the side walls are closely positioned so that a single blind at a time will pass there-between and being dried by a series of infra red lamps 67 positioned on the inner side of both walls and being directed toward each other so that heat produced thereby will contact both sides of the blind simultaneously for rapid evaporation of moisture deposited on the blind while passing through the rinsing chamber, and switch means to make and break the electric current for the lamps wholly or in part from the upper rows of lamps downward as desired are controlled.

A further modification resides in the carrying means for the blinds through the medium of a coupling having a loop 68 on one end thereof to engage the carrying bar of the blinds, while on the other end of the coupling is a hook 69 to engage on a knuckle 10 that rockably connects the links of the chain. By this arrangement the blinds are removed from the chain when laundered. In this modification the single track and chain belt extend through all of said chambers whereby the switch and series of track are eliminated, and such other modifications may be made as lie within the scope of the appended claims.

Having fully described my invention, what I claim as new and desire to secure by Letters Patent is:

1. In a washing machine for window blinds, of the class described, a tank for containing washing fluid, a heating pipe positioned in the tank to be submerged by the fluid, means to circulate heat through the pipe to heat the washing fluid, a pair of hollow walls seated in spaced relation on the tank, a plurality of nozzles for each wall, the nozzles being in spaced relation on the confronting sides of their respective walls, a motor-actuated pump, and pipe means to connect the pump to the tank and said hollow walls to circulate fluid from the tank through the walls and outward through the nozzles as washing means for Venetian blinds pendants carried between the hollow walls, there being conveying means for the blinds between said hollow walls.

2. In a washing machine for window blinds, of the class described, a tank rectangular in form and of suitable depth, the upper extremity of

which is open, a heat-conducting pipe entering at one side, running to and fro through the tank and outward therefrom for a desired temperature of washing fluid contained in the tank, a pair of hollow walls upwardly extending from the tank, means carried by the tank to support the walls concentric to the opening of the tank, a pump connected with the hollow walls and interior of the tank as circulating means for washing fluid contained in the tank through said hollow walls, a 10 series of nozzles distributed over confronting sides of the hollow walls, the nozzle series to eject water toward each other under pressure from the pump to wash a set of Venetian blinds on both sides thereof simultaneously while said 15 blinds are moved continuously between the hollow walls, and pendant carrying means for the blinds.

3. In a washing machine for window blinds, of the class described, a tank as a container for water, a heating duct of suitable diameter extending through the tank and being submerged by the water as heating means therefor, a pair of hollow walls in spaced relation carried by the tank, a plurality of nozzles for each wall, the nozzles being in spaced relation on the confronting sides of their respective walls, a pump having pipe means to connect the pump to the tank and said hollow walls to force water from the tank into the walls and outward through the nozzles as 30 washing means for Venetian blinds pendants carried between said hollow walls, and a pair of rubber flaps to close each end of the space between the hollow walls.

4. In a washing machine for window blinds, of the class described, a tank, a tubular heating pipe positioned in said tank for heating water in said tank, said pipe having straight portions and arced joints to connect the straight portions to increase the length of the pipe as coupled, 40 means to circulate and heat the air for said pipe, a pair of vertically positioned hollow members having a hollow member to connect the same at their lower extremities, bars to support the hollow members above said tank, and a plurality of spray nozzles for the confronting sides of the vertically disposed hollow members, said nozzles being evenly distributed in spaced relation over the entire area of the said sides.

5. In a washing machine for window blinds comprising a tank as a water container, a spray washing mechanism positioned on the tank, a conveyor for Venetian blinds in working relation to the washing mechanism, said washing mechanism comprised of a pair of hollow elements substantially rectangular in form and a hollow bottom communicatingly connecting the hollow elements, said hollow elements being spaced apart by the bottom so that the blinds may be conveyed between the hollow elements, nozzles plurally applied to the confronting sides of the said hollow elements, and a pump for circulation of the water from the tank into the hollow elements and outward through the nozzles as washing means for both sides of Venetian blinds simultaneously, said water returning to the tank.

6. In a washing machine for window blinds, as recited in claim 5, pipes connecting the said hollow elements with the tank and said pump for circulation of the water.

7. In a washing machine for window blinds, a hollow U-shaped structure having upwardly extending legs rectangular in form and being spaced apart by its hollow crotch, the latter as communicating means for water into the legs, a plurality of nozzles uniformly spaced over confronting sides of the legs for spraying hot water from leg to leg across the space therebetween, a tank for heated water, said tank being open at the upper extremity and upon which the U-shaped structure is seated, a duct extending to and fro within the tank and terminating in spaced relation a short distance inward from each wall of the tank, and means to produce and cause circulation of hot air through the duct to heat the water.

8. In a washing machine for window blinds, a hollow U-shaped structure having upwardly extending legs rectangular in form and being spaced apart by its hollow crotch, the latter as communicating means for water into the legs, a plurality of nozzles uniformly spaced over confronting sides of the legs for spraying water from leg to leg across the space therebetween, and a tank on which the hollow structure is seated, said tank being a catch basin for water as it leaves the U-shaped structure.

OGLE F. FRENCH.
